UNITED STATES PATENT OFFICE.

SAMUEL J. SHIMER, OF MILTON, PENNSYLVANIA.

CUTTER-HEAD.

SPECIFICATION forming part of Letters Patent No. 651,728, dated June 12, 1900.

Application filed April 13, 1900. Serial No. 12,703. (No model.)

To all whom it may concern:

Be it known that I, SAMUEL J. SHIMER, a citizen of the United States, residing at Milton, in the county of Northumberland and State 5 of Pennsylvania, have invented new and useful Improvements in Cutter-Heads, of which the following is a specification.

My present invention relates to cutter-heads; and the object of the same is to provide a cutter-head with bit-seats arranged alternately in pairs upon the upper and lower sides of each quarter-section of the head and to locate one of each pair of seats farther from the center of the head than the other 15 in order that the greatest possible difference may be attained between the surface cut of one bit and the extreme cut of the other bit and at the same time to attain this result with bits of the smallest relative diameters. This 20 object is attained by means of the construction shown in the accompanying drawings, which form a part of this specification, and in which—

Figure 1 is a perspective view of a cutter-head made in accordance with my invention. Fig. 2 is a bottom plan view of the same. Figs. 3 and 3^a are plan views of the two sections of the expandible head separated. Fig. 4 is a perspective view of one of the cutters. Fig. 30 5 is a similar view of the companion cutter.

Like letters and numerals of reference designate like parts wherever they occur in the different views.

In the drawings the numeral 1 designates 35 the upper section of the cutter-head, and 2 the lower section of the same. On each section of the head two pairs of bit-seats are formed, one of each pair being of larger diameter than the other. The seats of the 40 larger diameter are designated by the numeral 3, and those of the smaller diameter are designated by the numeral 4. The two sections 1 and 2 of the head are relatively expandible, and the flanges 5 and 6 of these sections are eccentric—that is to say, the distance from the point *a* to the axial center *X* of the head is greater than the distance from point *b* to said axial center. The result of this construction is that even with a bit of 45 50 comparatively - small diameter, like 7, the cutting edge will extend a sufficient distance

from the center or axis of the head to cut a comparatively-deep groove, while its companion bit, like 8, will cut a surface at the side of the groove at a greater relative distance from the bottom of the groove than could result were the two companion bits set concentric with the axis and the same relative size maintained. This feature is of considerable importance, as it increases the scope 60 of the cutters, and while I have shown bits of a certain type for cutting a central groove and two opposite mold-surfaces it will be obvious that this feature may be applied to cutters of widely-different contours. 65

It will be observed that by setting the two sections of the cutter-head eccentrically sufficient space is given to free the noteh in the bit 8 to facilitate the sharpening of its cutting edge. It will also be noted that in order 70 to maintain a proper running balance the two companion bits must be located within each quarter-section of the circumference of the head, either upon the one and the same center or side by side, as shown. When located 75 side by side, the differential bit-centers figure as important factors by way of keeping the bit-seat diameters of the two bits as small as possible in order that they may be located within the limited space afforded by each 80 quarter-section of the head and each pair of bit-seats opposite each other pair to properly maintain a true running balance. The bolt-holes 10 for the bits 7 are located nearer to the edges of the flanges 5 and 6 than the bolt-holes 11 for the bits 8, and this arrangement 85 also gives some differential scope to each pair of bits.

Having thus fully described my invention, what I claim is—

1. A cutter-head having circular bit-seats arranged in pairs, each pair occupying a quarter-section of the circumference of the cutter-head, and one seat in each pair being located farther from the center of the head than the other, substantially as set forth. 95

2. A cutter-head comprising two expandible sections provided with eccentric flanges, bit-seats formed in said flanges in pairs, each pair of seats being located within a quarter-section of the circumference of the head, and one bit-seat in each pair being located far- 100

ther from the center of the head than its companion, substantially as described.

3. A cutter-head consisting of two expandable sections, each provided with eccentric flanges, bit-seats located on said flanges in each quarter-section of the head, said bit-seats being arranged in pairs, one seat in each pair being located at a greater distance from the axis of the cutter-head than its com-

panion, and bits secured by bolts in said seats, substantially as described.

In testimony whereof I have hereunto set my hand in presence of two subscribing witnesses:

SAMUEL J. SHIMER.
